Filed Aug. 13, 1973, Ser. No. 387,900

Term of patent 14 years

Int. Cl. D26—04

U.S. Cl. D73—1 B

FIG. 1

FIG. 2

FIG. 3

FIG. 4

FIG. 1 is a front elevational view of a multiple wick candle of dodecahedron shape showing my new design,

FIG. 2 is an elevational view of the candle with the candle rotated horizontally through thirty-six degrees from its position in FIG. 1,

FIG. 3 is a top plan view, and

FIG. 4 is a bottom plan view.

The characteristic feature of my design resides in the provision of a circular recess with centrally projecting wick on every candle face.

I claim:

The ornamental design for a multiple wick candle of dodecahedron shape, as shown.
